UNITED STATES PATENT OFFICE

158,067

DESK THERMOMETER

Robert E. Gordenier, St. Paul, Minn., assignor to
Brown & Bigelow, St. Paul, Minn., a corpora-
tion of Minnesota

Application October 29, 1947, Serial No. 142,191

Term of patent 3½ years

(Cl. D52—7)

To all whom it may concern:

Be it known that I, Robert E. Gordenier, a citizen of the United States, residing in St. Paul, county of Ramsey, and State of Minnesota, have invented a new, original, and ornamental Design for a Desk Thermometer, of which the following is a specification, reference being had to the accompanying drawings, forming part thereof:

Figure 1 is a front elevation of a desk thermometer, showing my new design.

Figure 2 is a rear view thereof, with the easel support in flattened position.

Figure 3 is a side view thereof in position for use.

Figure 4 is a partial sectional view on the line 4—4 of Figure 1.

I claim:

The ornamental design for a desk thermom-
eter, as shown.

ROBERT E. GORDENIER.
